CLAIM

I claim the ornamental designs for a line attachment device, as shown and described.

DESCRIPTION

FIG. 1 is a perspective view of the top side of the line attachment device;

FIG. 2 is a perspective view of the bottom side of the line attachment device of FIG. 1;

FIG. 3 is a perspective anterior view of the line attachment device of FIG. 1;

FIG. 4 is a top view of a first side of the line attachment device of FIG. 1;

FIG. 5 is a bottom view of the line attachment device of FIG. 1;

FIG. 6 is an anterior view of the line attachment device of FIG. 1;

FIG. 7 is a posterior view of the line attachment device of FIG. 1;

FIG. 8 is a side view of a first side of the line attachment device of FIG. 1; and,

FIG. 9 is a side view of a second side of the line attachment device of FIG. 1.

1 Claim, 9 Drawing Sheets
